FRED E. ASELTINE, OF DAYTON, OHIO, ASSIGNOR TO DELCO PRODUCTS CORPORATION,
OF DAYTON, OHIO, A CORPORATION OF DELAWARE

DUPLEX CHARGE FORMING DEVICE

Application filed November 2, 1929. Serial No. 404,321.

This invention relates to charge forming devices for internal combustion engines, and more particularly to devices of this character which comprises a plurality of primary carburetors, each of which delivers a primary mixture of fuel and air to one of a plurality of secondary mixing chambers located adjacent the engine intake ports, and in which the primary mixture is mixed with additional air under certain operating conditions.

An example of charge forming device of this character is disclosed in the application of Fred E. Aseltine, Wilford H. Teeter, Carl H. Kindl and Frederick D. Funston, Serial No. 370,179, filed June 12, 1929.

The principal object of the present invention is to provide a novel charge forming device which is effective to secure equal distribution of the fuel charge to the various cylinders of multicylinder engines, particularly engines having more than four cylinders.

According to the present invention, this object is attained by the provision of an air manifold having two entirely separate passages formed therein, each of which communicates with half of the cylinders, the groups of cylinders with which each passage communicates preferably having the same firing order. The carburetor unit is provided with a plurality of primary carburetors and in the specific embodiment disclosed herein, these are of the type shown in the above mentioned application, and each communicates with one of the outlet branches of the above manifold. The carburetor unit is provided with two separate air passages, one of which communicates with each of the air passages in the manifold and each of which is supplied with air from a main air chamber communicating with the atmosphere through a single air inlet. A partition is provided in the air chamber which divides such chamber into two chambers or passages, each of which communicates with one of the aforementioned passages and also supplies air to a plurality of the primary carburetors in the manner hereinafter described, while the admission

of air to this divided chamber is controlled by a single suction-operated valve having a slot therein which embraces the partition.

Further objects and advantages of the present invention will be apparent from the following description, reference being had to the accompanying drawings wherein a preferred embodiment of one form of the present invention is clearly shown.

In the drawings:

Fig. 1 is a plan view of a charge forming device embodying this invention, said view being drawn on a smaller scale than the other views in order to show the entire structure.

Fig. 2 is a front elevation of the carburetor unit and one end of the associated manifold, the other end being broken off as indicated.

Fig. 3 is a side elevation of the main carburetor unit viewed from the right in Fig. 1, and partly broken away to show further parts in section.

Fig. 4 is a side elevation of the main carburetor unit viewed from the left in Fig. 1, and partly broken away to show certain parts in section.

Fig. 5 is a vertical section on the line 5—5 of Fig. 1.

Fig. 6 is a horizontal section on the line 6—6 of Fig. 5.

Fig. 7 is a horizontal section on the line 7—7 of Fig. 5 looking upward.

Figs. 8 and 9 are fragmentary sections showing the fuel supply passages.

Fig. 10 is a fragmentary, horizontal section on the line 10—10 of Fig. 5, certain parts being omitted.

Fig. 11 is a fragmentary plan view of the air chamber.

The device disclosed herein comprises a main air manifold indicated in its entirety by the reference numeral 10. This main manifold is divided into two separate manifolds or headers 12 and 13, as indicated in Figs. 1 and 2, and each of these headers is provided with two outlet branches, the branches of the header 12 being numbered 14 and 16 and those of the header 13 being numbered 18 and 20. These outlet branches

communicate with the intake ports of an eight-cylinder engine and are each provided with an attaching flange 22 for securing the manifold to the engine block in the usual manner and another flange 24 to the inlet end of the manifold to which the carburetor unit may be secured. Each of the headers 12 and 13 is provided with a separate intake passage, these being numbered 26 and 28 respectively. These intake passages are adapted to communicate when the device is assembled, with two separate air passages 30 and 32 formed in the carburetor unit in the manner hereinafter described, and the outlet branches of the headers 12 and 13 communicate with groups of four cylinders of the eight-cylinder engine, such groups of cylinders preferably having the same firing order so that the manifold in effect really divides the eight-cylinder engine into two four-cylinder engines, each of which is supplied with fuel mixture by a separate intake passage.

The carburetor unit comprises a main housing 34 having an attaching flange 36 adapted to be secured to the flange 24 by screws 38. An air inlet coupling 40 is secured in position in an opening in the upper wall of the housing 34 in any suitable way and may be connected with an air cleaner if desired. A casting 42, in which the passages supplying fuel to the nozzles are formed, is secured by screws (not shown) to the lower wall of the main housing and a sheet metal fuel bowl 44 is held tight against an annular shoulder 46 on the housing by any suitable means such as a screw 48 extending into a depending portion of the casting 42.

40 Fuel is conducted from a main source of supply through a conduit (not shown) to an angular fuel passage 50 formed in the wall of the main housing and communicating with a vertical passage 52 in the casting 42.

45 Communicating with the latter passage is a restricted passage 54 within a nipple 56 screwed into the casting 42. A fuel valve 58 cooperates with the restriction in the passage 54 to regulate the admission of fuel to the float chamber, said valve being controlled by a float 60, which operates to maintain a substantially constant level of fuel in the float chamber.

55 A plurality of angular primary mixture passages indicated in their entirety by the reference numeral 62 and hereinafter more fully described, are formed in the lower part of the main housing 34, and communicating with the vertical portion of the mixture 60 passages 62 through orifices 64 are chambers 66, which may be designated fuel supply chambers for convenience. Fuel is admitted directly to these chambers by means hereinafter described, and is mixed with a small 65 quantity of air admitted to said chambers

by an opening 68, formed in a partition separating the fuel chambers from a main air chamber as more fully described hereinafter. Communicating with each of the fuel supply chambers are nozzles 70, each of which is provided with a main fuel outlet 72 in the top of the nozzle and secondary fuel outlets 73 and 74 formed in the vertical wall of the nozzles close to the bottom of the said fuel supply chambers. The suction within the fuel supply chambers is sufficient to effect a flow of fuel from the main fuel outlet only when the engine is running at relatively high speed, while the secondary fuel outlets are effective to supply fuel at all speeds, and to supply all the fuel at relatively low speeds, when the suction is sufficient to lift the fuel in the nozzles only to a point between said secondary fuel inlets and the main fuel inlet, the fuel flowing from the former by the action of gravity.

Fuel is conducted from the float chamber to the nozzles through a vertical passage 80, formed in the casting 42 and illustrated in Figs. 6 and 8. This passage communicates at its upper end with a horizontal channel 82, which communicates with a short vertical channel 84 connecting with a horizontal fuel canal 86, which is shown in plan in Fig. 6. The passage 86 extends an equal distance on both sides of the passage 84 and at its ends, communicates with two passages 88 arranged at an angle thereto, the passages 88 communicating with the fuel nozzles directly. The nozzles are positioned immediately above the ends of the passages 88, so that the distance through which the fuel flows from the passage 84 to each nozzle is the same, this construction being provided so that equal distribution is secured because the frictional resistance to the flow of fuel from the passage 84 to each nozzle and the time required for the fuel to reach each nozzle is substantially the same.

Fuel is supplied to the vertical passage 80 at all times through a calibrated plug 90, having a fixed orifice therein and communicating directly with the fuel in the fuel reservoir. After a certain predetermined throttle movement, a valve 92, normally held closed by spring 94, is opened by means to be later described, to permit a flow of fuel from the reservoir 44 around said valve into a bore 96, formed in the casting 42, and thence through a metering plug 98, screwed into the bore, to a horizontal passage 100, which communicates with the passage 80, as shown in Fig. 4. Additional fuel is supplied by the above described passages to provide the necessary quantity of fuel demanded by the engine when operating at relatively high speeds.

A still further means for supplying additional fuel to the nozzles under certain conditions comprises a fuel port 102, controlled

5 by a valve 104, which may be manually operated by means to be later described. This valve is normally held in position to close the port 102 by a spring 106, received in a bore 108 in the casting 42 below the valve. When the valve is depressed fuel is admitted through the port and flows through said bore 108 and a metering plug 110 screwed into said bore, into a vertical 10 passage 112, communicating at its lower end with the bore 108, and at its upper end with the horizontal passage 114, which connects with the passage 84.

15 The primary mixture passages are controlled by a single throttle valve 116, which extends across all of the passages and is provided with grooves 118, which are adapted to register with said passages, as fully described in the above mentioned, earlier application.

20 The fuel supply chambers 66 communicate with chambers 120a and 120b which may for convenience be termed primary air chambers. These chambers and the fuel supply 25 chambers 66 are separated from main air chambers 122a and 122b by means of a partition plate 124 and the chambers 66 are also separated from the vertical portions 30 of the primary mixture passages by a vertical partition 126, which is a part of the main casting and on which the plate 124 is supported. Other vertical partitions 128 separate the fuel supply chambers from each other and these partitions are also formed 35 integrally with the main housing. All of the air admitted to the carburetor is supplied through the air inlet coupling 40 and is controlled by a valve 130 normally held 40 against its seat 132 by a spring 134, which is received between the valve and a flange 136, projecting from a sleeve 138, slideable on a sleeve 140, secured in the main housing in any desirable manner, and forming a 45 guide for the valve stem 142 to which the valve 130 is secured. Secured to the lower face of the valve 130 is a sleeve 144, which surrounds the spring 134 and fits within a sleeve 146, extending upwardly from the partition 124, previously described. These 50 cooperating sleeves are provided to more accurately guide the air valve in its reciprocatory opening and closing movements. Under normal conditions, the flange 136 occupies the position shown in Fig. 5, but may 55 be lifted from this position by the choke mechanism for the purpose of holding the air valve closed to facilitate starting.

60 The choke mechanism comprises a bell crank lever having a hub 150 rotatably mounted on a spindle 152, secured in lugs projecting from the main housing. An arm 154 projects through the wall of the housing from the hub 150 and engages the lower side of the flange 136 while another arm 156 integral with the hub 150 is adapted to be

connected to some form of operating connection extending to a point convenient to the operator of the vehicle so as to enable the operator to lift the flange 136 if desired. The mechanism previously described, while not exactly the same as that shown in the earlier application above referred to, is very similar thereto and forms no part of the present invention.

65 Heretofore, as in the above mentioned application, all the primary mixture passages and secondary or auxiliary air passage have each been supplied with air from a single primary and secondary air chamber respectively. According to the present invention, however, the main air chamber is divided into the chambers 122a and 122b by vertical partition plates 160 and 161, which at their top are provided with projections 163, which fit in grooves 162 in the inner wall of the 70 main housing, while below these projections, the edges of the plates contact with the inner wall of the main housing. The inner edges of the plates 160 and 161 extend to the sleeves 144 and 146. A vertical partition 165 integral with the main housing, similarly divides the primary air chamber into the separate chambers 120a and 120b. Each of the chambers 120a and 120b 75 communicates with two of the fuel supply chambers 66, which supply a primary emulsion of fuel and air to two of the primary mixture passages 62, while the chambers 122a and 122b communicate directly with secondary air passages 30 and 32 respectively, the passage 30 thus supplying air to the passage 26 and header 12, while the passage 32 supplies air to the passage 28 and header 13. The air valve 130 is provided with slots 80 164 and 166 into which the partitions 160 and 161 extend, the valve sliding on the partition as it moves up and down. It will be clear that the valve controls the admission of air to both of the chambers 122a and 122b. The flow of air through the passage 30 is controlled by a manually operable air throttle 168, secured to a shaft 170, journaled in the main housing and by a suction operated valve 172, secured to a shaft 174, which is also journaled in the 85 housing and is arranged off center with respect to the valve 172. The flow through the passage 32 is controlled by a valve 176 also secured to the shaft 170 and a suction operated valve 178 secured to the shaft 174 so that similar valves in the two passages 30 and 32 operate together as a unit. The operating mechanism for these valves will 90 be described in detail hereinafter. In addition to the air supplied through the primary air chambers 120a and 120b to the primary mixture passages, the vertical portions of these passages are constructed to communicate with the two air chambers 122a and 122b, two of the primary mixture 95 100 105 110 115 120 125 130

passages being supplied with air in this manner by each of said air chambers.

The opening 68 extends on both sides of the above described partitions 160 and 161 so as to admit air to each of the chambers 120a and 120b and the area of this opening is considerably larger than the total area of the orifices 64, which connect the fuel supply chambers 66 with the primary mixture passages. In view of this difference in area, it will be obvious that the flow of air through the chambers 120a, 120b and 66 communicating therewith must necessarily be relatively slow. Because of the low velocity of the air passing the fuel nozzles, there is substantially no velocity head created at such nozzles under any operating condition, or at any operating speed. Air is admitted through the opening 68 more rapidly than it can be exhausted through the orifice 64, hence there is substantially no difference in the pressure maintained on opposite sides of the partition plate 124. The suction at the fuel nozzles, therefore, is at all engine speeds substantially the static suction maintained in the chambers 122a and 122b, as determined by the spring 134, which controls the opening of the main air valve.

During operation at all engine speeds below a certain predetermined speed, for example, that corresponding to a vehicular speed of 20-25 miles per hour on a lever, the mixture supplied to the engine by the primary mixture passages is of properly combustible proportions and is conveyed to the engine without mixture with additional air in the secondary mixing chambers, to be described later. At higher engine speeds than this, the valves controlling the flow of air through the secondary air passages are opened to supply additional air and increase the quantity of mixture supplied to the engine.

The shaft 170, on which the valves 168 and 176 are secured, is operated by the primary throttle after said throttle has made a certain amount of independent movement, subsequent to which movement the valves 168 and 176 are moved simultaneously therewith. For this purpose the primary throttle is provided with an operating arm 180, secured to the end of the throttle by means not shown herein, but fully disclosed in the above mentioned application. The arm 180 is provided with a hole 182 in its free end in which any suitable form of operating connection extending to a point convenient to the operator, is adapted to be secured. Secured to the arm 180, by means of a screw 184, is an arm 186 carrying a stop screw 188, adapted to engage a fixed stop, as shown in the earlier application, to limit the closing movement of the throttle. By adjusting the stop screw, the normal closed

position of the throttle may be regulated as desired to determine the idling speed of the engine.

Secured to the other end of the primary throttle, in the manner disclosed in the above mentioned application, is an operating plate 190, to which a link 192 is pivotally connected by a screw 194. The upper end of the link is pivotally connected to a pin 196, projecting from an arm 198, secured to the shaft 170. The pin 196 is received loosely within a slot in the end of the link 192 to prevent binding of the parts and the pin is normally held in the bottom of this slot by a spring 200, connecting said pin and a pin 80 projecting from the link 192. The parts are so arranged that when the primary throttle is opened, the screw 194 moves in a clockwise direction and during the first part of its movement such screw moves in the arc 85 of a circle, the center of which is the pin 196, so that while moving in this arc the arm 190 is ineffective to move the pin 196. This movement takes place during the first 90 part of the opening movement of the primary throttle and after the latter has moved through a predetermined distance, the screw 194 no longer moves in such an arc but its movement is effective to lift the link 192 and move the pin 196 in a clockwise direction 95 opening the valves 168 and 176. Closing or counterclockwise movement of the primary throttle will move the link 192 downwardly and obviously move the valves 168 and 176 toward closed position.

The valves 172 and 178, which are secured to the shaft 174, are adapted to be opened entirely by engine suction, but until the manually operable valves 168 and 176 are opened, as previously described, the suction 100 operated valves are held closed by a bifurcated lever 202, which is pivoted on a pin 204, projecting from the primary throttle. This lever is urged toward closed position to hold the suction operated valves closed 110 by a spring 206, connected to an arm 208, projecting from the bifurcated lever and to the main housing, as shown in Fig. 4. In order to enable the closing of the valves 172 and 178 by the means above described, an 115 arm 210 is secured in any desirable manner to the end of the shaft 174 and is pivotally connected at its free end to the bent link 212, the lower end of which is connected to a dash-pot piston to control the opening 120 movement of valves 172 and 178, in a manner to be later described. This link is received between the two arms of the lever 202 and the pin 214 on said link is engaged by one arm of said lever, whenever it is 125 moved in a counterclockwise direction by the spring 206, closing the valves 172 and 178 and holding such valves closed during the first part of the opening movement of the throttle. In order to permit the open- 130

ing of the valves 172 and 178 by engine suction, it is obvious that the lever 202 must be moved out of engagement with the pin 214 and this is accomplished by the throttle 5 operating mechanism when the latter has made a predetermined amount of opening movement. For this purpose a pin 216 is secured to the operating plate 190 and projects therefrom so as to engage one arm of 10 the lever 202 as the plate is moved in a clockwise direction, rocking the lever downwardly and moving it out of engagement with the pin 216, as fully described in the earlier application above referred to.

15 On opening movement of the primary throttle or the valves 168 and 176, the suction effective on the air valve is increased and the latter is opened against the pressure of its spring to permit an increased flow of 20 air past said valve into the chambers 122a and 122b and thence into the passages 30 and 32. It has been found that during opening movements of said valve it will flutter if allowed to open freely and to prevent 25 fluttering, a dashpot of conventional form is provided. This dashpot consists of a cylinder 220, formed in the casting 42 and a piston 222 cooperating therewith and secured to the lower end of the air valve stem 30 142 by a nut 224. Small orifices 226 are provided in the dashpot piston and are adapted to be normally closed by a check valve 228, 35 slidable on the valve stem immediately above the piston. An orifice 230 is formed in a plate 232, which is secured to the bottom of the casting 42 to close the above mentioned cylinder 220, and other cylinders formed in the casting 42. The dashpot is of substantially conventional construction and retards the 40 opening of the air valve to the extent determined by the sizes of the orifices 226 and 230.

The check valve 228 is provided to prevent a tendency of the air valve to enrich 45 the mixture by gradually moving toward closed position because of the effect of engine pulsations at relatively low speeds. The check valve provides a greater resistance toward closing movement of the valve 50 than the dashpot provides toward opening movement so that the above mentioned effect of the engine pulsations is eliminated as more fully described in the earlier application:

55 On any opening movement of the throttle, it is found necessary to enrich the mixture to some extent in order to properly operate the engine during the acceleration period. For this purpose the device disclosed is provided with a fuel pump operated by the primary throttle and designed to temporarily supply additional fuel to the primary mixture passages, in the manner hereinafter described. It has also been found necessary 60 65 in order to secure the desired enrichment to

provide means for retarding the opening of the suction operated valves 172 and 178 whenever the valves 168 and 176 are opened. This is necessary in order to produce a sufficient pressure differential between the inlet and outlet ends of the primary mixture passages to create a velocity of flow there-through great enough to transport the enriched primary mixture from the fuel supply chambers to the secondary mixing chambers substantially instantaneously. The primary mixture must pass through a considerable distance and if the suction operated valves were permitted to open freely, an appreciable time interval would be required 70 for the rich and relatively heavy primary mixture to travel through this distance, obviously a greater time interval than that required for pure air to travel from the manually operable valves 168 and 176 to the secondary mixing chambers. By retarding the opening of the suction operated valves, the time interval necessary for the primary mixture to reach the secondary mixing 75 chambers is reduced, while that necessary for the air to reach said chambers is increased until these intervals become substantially equalized, with the result that the enriched primary mixture and secondary air reach the secondary mixing chambers at 80 85 substantially the same time.

In order to retard the opening of the valves 172 and 178, the link 212, hereinbefore referred to, is pivotally connected at its inner end in any desirable way to a dashpot piston 236, which is slidable in a cylinder 238 formed in a casting 42 and closed at the bottom by the plate 232, previously referred to. A valve cage 240 having a passage 242 therethrough, is secured in the plate 232 so that the passage will admit fuel to the cylinder 238 from the main fuel reservoir when a check valve 244, received in said valve cage is unseated. Upward movement of this check valve is limited by the pin 246 positioned above the valve and it will be obvious that upward movement of the piston 236 is substantially unretarded, as the check valve is then opened, but downward movement of the piston, which takes place on opening of the valves 172 and 178, is retarded to delay the opening of said valve. 90 95 100 105 110 115

In order to regulate the retarding effect of the above described dashpot so as to retard the opening of the valves to substantially the same extent for the same opening movement of the throttle regardless of the position the valves may occupy when their opening movement begins, an auxiliary cylinder 248 is provided which is positioned in the casting 42 substantially adjacent the cylinder 238 and connected therewith by a passage 250 at the bottom of the cylinders, as shown in Fig. 7. Slidable within the cylinder 248 is a piston 252, which is normally 120 125 130

held in the position shown in Fig. 5 by a spring 254, received between the piston and the top of its cylinder. On downward movement of the piston 238, the piston 252 is lifted by the pressure effective on the bottom of said piston and the fuel in the cylinder above the piston is forced out of an orifice 256 near its top, the rate of escape of fuel through this orifice determining the retarding effect of the dashpot on the valves 172 and 178. After the valves have completed any opening movement, the spring 254 forces the piston 252 downwardly until it assumes the position it occupied at the beginning of the opening movement of said valves and the cylinder 248 is filled with fuel from the main fuel reservoir through the orifice 256 above referred to. It should be clear, therefore, that the piston 252 occupies the same position whenever an opening movement of the valves 172 and 178 takes place and the retarding effect of the dashpot on these valves must be substantially the same for every opening movement thereof following the same amount of throttle movement.

The pump for supplying additional fuel to the primary mixture passages is operated by the primary throttle during its opening movement. This pump comprises cylinder

258, formed in the casting 42 and a piston 260, slideable therein. The piston is operated by a rod 262, pivotally connected to pin 216, which projects from the operating plate 190.

35 The rod is not actually connected to the pump piston but the lower end of said rod is received inside of a tube 264, projecting upwardly from the piston and is adapted to engage the piston when the parts are in 40 the position shown in Fig. 4 with the throttle closed, the piston being held in this position by spring 266, which is received in the cylinder below the piston 260. When the throttle is moved in a clockwise direction to

45 open it, the rod 262 is moved downwardly and moves the piston correspondingly, while on closing movements of the throttle, the piston is lifted by the spring as the rod moves upwardly. The pump cylinder com-

50 municates with a fuel delivery conduit 268, formed in the bottom of the casting 42 and communicating with the vertical passage 270, which at its upper end communicates with a horizontal passage 272, and is enlarged immediately below such passage to receive a check valve 273, which cooperates with a seat 275, to prevent the return of fuel to the pump cylinder after each operation of the pump. The passage 272 supplies

55 fuel to an open well 274, communicating with the atmosphere through an opening 276 so that atmospheric pressure is maintained in the well. Passages 278 conduct fuel from the well to vertical passages 280,

60 which communicate with restricted passages

282, formed in the wall of the main housing and communicating with the primary mixture passages. Communicating with the passages 278 are vertical air passages 284 receiving air from the opening 276, as shown 70 in Fig. 6, and the ends of the passages 278 are also open and communicate with the space above the fuel in the fuel reservoir 44, so that air is admitted to the passages 278 forming therein an emulsion of fuel and air 75 which is carried into the primary mixture passages on any downward movement of the pump piston substantially in the same manner as described in the earlier copending application. Fuel flows from the well into the passages 278 by the action of gravity and is mixed with the air supplied thereto to form an emulsion of fuel and air which is drawn into the primary mixture passages by the suction therein. Air is admitted 80 through the various passages so that the suction in the fuel delivery conduit is never sufficient to draw fuel from the pump cylinder and fuel can only be delivered to the mixture passages on operation of the pump. 85

It will be noted that the rod 262 is provided with an arm 286 which has an ear 288 projecting therefrom so as to engage the fuel valve 92 as the pump piston moves downwardly. 90

The manually operable valve 104 herein-before referred to, is provided primarily for the purpose of regulating the fuel supply in accordance with seasonal variations, but may be opened or closed whenever it is deemed desirable. The means for opening such valve comprises a plunger 290, which is rotatable in the main housing and engages the top of the valve 104. The plunger 290 is provided with means (not shown) for effecting vertical movement of the plunger on rotation thereof so as to open or close the valve as desired. 100

The primary mixture passages 62 communicate with primary mixture tubes 292, 294, 296, and 298, tubes 292 and 294 supplying fuel mixture to the outlet branches of the header 12, while the tubes 296 and 298 supply primary mixture to the outlet branches of the header 13. Thus, it will be seen that two of the primary mixture passages supply fuel to the outlet branches of one header which supplies mixture to four of the engine cylinders, while the other two passages supply mixture to the branches of the other header, which supplies mixture to another group of four cylinders of the engine and the two headers referred to are entirely separate from each other. 110

The tubes above referred to comprise alternately round and flat sections indicated at 200 and 202 respectively, the flat sections being straight and the round sections forming the bends of the tubes. These tubes are cast in position in the manifold during the 120

casting of the latter and the alternate round and flat construction of the tubes effects an alternate expansion and contraction of the mixture passing therethrough, which tends 5 to form a more homogeneous mixture than would be possible with tubes having the same cross sectional area throughout. The flat sections of the tubes also increase the velocity of flow therethrough because of the 10 reduction in cross sectional area of those sections, and the bottom of the tubes being substantially flat in these sections, the surface over which the fuel flows is considerably increased so that there is a greater 15 tendency for evaporation and less condensation of the fuel on the wall of the tube. The secondary mixing chambers may comprise any desirable means for straightening the flow of air past the ends of the primary mixture tubes and increasing the velocity of 20 flow at such point. No means of this character is illustrated herein and any form of such device which has been used in earlier devices of this character may be employed. 25 The construction of the device disclosed in this application is very similar to that disclosed in the earlier case referred to, with the exception of the divided air chambers and plurality of secondary air 30 passages in the carburetor units, the separate passages formed in entirely separate parts of the manifold, so arranged that each passage supplies combustible mixture to one of two groups of four cylinders of an eight- 35 cylinder engine separately and the present invention relates to these features.

While the form of embodiment of the present invention as herein disclosed, constitutes a preferred form, it is to be understood that other forms might be adopted, all coming within the scope of the claims which follow.

What is claimed is as follows:

1. A charge forming device for a multi-cylinder internal combustion engine comprising a plurality of mixing chambers, means for supplying fuel to said mixing chambers, an air chamber for supplying air to said mixing chambers having a partition 45 therein dividing said chamber into two passages each of which communicates with one of said mixing chambers, and a single air inlet admitting air to both of said passages. 50 55 60 65

2. A charge forming device for a multi-cylinder internal combustion engine comprising a plurality of mixing chambers, means for supplying fuel to said mixing chambers, an air chamber for supplying air to said mixing chambers having a partition therein dividing said chamber into two passages each of which communicates with one of said mixing chambers, a single air inlet admitting air to both of said air passages, and a suction operated valve in said inlet

regulating the flow of air through both said air passages.

3. A charge forming device for a multi-cylinder internal combustion engine comprising a plurality of mixing chambers, means for supplying fuel to said mixing chambers, an air chamber for supplying air to said mixing chambers having a partition therein dividing said chamber into two 70 passages each of which communicates with one of said mixing chambers, a single air inlet admitting air to both said air passages, a suction operated valve in said inlet regulating the flow of air through both said air 75 passages, and a slot in said valve in which said partition is received. 80

4. A charge forming device for a multi-cylinder internal combustion engine comprising, a plurality of mixing chambers, means for supplying fuel and air thereto, a plurality of auxiliary air passages for supplying air to said mixing chambers, an air chamber supplying air to said auxiliary air passages, a partition in said chamber dividing it into two separate parts, each of 85 which communicates with one of said passages, and a single air valve controlling the admission of air to both parts of said air chamber. 90

5. A charge forming device for a multi-cylinder internal combustion engine comprising, a plurality of mixing chambers, means for supplying fuel and air thereto, a plurality of auxiliary air passages for 95 supplying air to said mixing chambers, an air chamber supplying air to said auxiliary air passages, a partition in said chamber, dividing it into two separate parts, each of which communicates with one of said passages, a single air valve controlling the admission of air to both parts of said air chamber, and a slot in said valve adapted to receive said partition. 100 105

6. A charge forming device for a multi-cylinder internal combustion engine comprising, a plurality of mixing chambers, fuel inlets therefor, a primary air chamber for supplying air to all of said mixing chambers, a plurality of auxiliary air passages for supplying air to said mixing chambers, a main air chamber for supplying air to said auxiliary air passages, and a partition dividing the main and primary air chambers into separate parts communicating with different auxiliary air passages and different mixing chambers respectively. 110 115

7. A charge forming device for a multi-cylinder internal combustion engine comprising a plurality of mixing chambers, fuel inlets therefor, a primary air chamber for 120 supplying air to all of said mixing chambers, a plurality of auxiliary air passages for supplying air to said mixing chambers, a main air chamber for supplying air to said auxiliary air passages, a partition dividing 125 130

- the main and primary air chambers into separate parts communicating with different auxiliary air passages and different mixing chambers respectively, and a single air valve controlling the admission of air on both sides of said partition.
8. A charge forming device for a multi-cylinder internal combustion engine comprising a plurality of mixing chambers, fuel inlets therefor, a primary air chamber for supplying air to all of said mixing chambers, a plurality of auxiliary air passages for supplying air to said mixing chambers, a main air chamber for supplying air to said auxiliary air passages and to said primary air chamber, and a partition dividing both the main and primary air chambers into separate parts, communicating with different auxiliary air passages and different mixing chambers respectively.

9. A charge forming device for a multi-cylinder internal combustion engine comprising a plurality of primary mixing chambers, means admitting fuel thereto, a plurality of secondary mixing chambers into which said primary mixing chambers deliver a mixture of fuel and air, a plurality of auxiliary air passages adapted to supply air to said secondary mixing chambers, a main air chamber through which air flows to said primary mixing chambers and to said auxiliary air passages, a partition dividing said air chamber into separate parts communicating with different passages and a single air valve controlling the flow of air through said chamber on both sides of the partition.

10. A charge forming device for a multi-cylinder internal combustion engine comprising a carburetor unit provided with means for forming a primary mixture of fuel and air, a manifold receiving primary mixture from the carburetor unit and adapted to supply a combustible mixture to the engine intake ports, a plurality of air passages in the manifold each of which communicates with only certain of said intake ports, a plurality of auxiliary air passages in the carburetor unit adapted to communicate with the air passages in the manifold and a single air inlet admitting air to said plurality of auxiliary air passages.

11. A charge forming device for multi-cylinder internal combustion engines comprising a carburetor unit provided with means for forming a primary mixture of fuel and air, a manifold receiving primary mixture from the carburetor unit and adapted to supply a combustible mixture to the engine intake ports, a plurality of air passages in the manifold each of which communicates with only certain of said intake ports, a plurality of auxiliary air passages in the carburetor unit adapted to communicate with the air passages in the manifold and a single air valve controlling the

admission of air to said plurality of air passages.

12. A charge forming device for multi-cylinder internal combustion engines comprising a carburetor unit provided with means for forming a primary mixture of fuel and air, a manifold receiving primary mixture from the carburetor unit and adapted to supply a combustible mixture to the engine intake ports, a plurality of air passages in the manifold each of which communicates with only certain of said intake ports, a plurality of auxiliary air passages in the carburetor unit adapted to communicate with the air passages in the manifold, a main air chamber in the carburetor unit supplying air to said plurality of auxiliary air passages, a partition in said air chamber dividing said chamber into separate parts each of which communicates with one of said auxiliary air passages, an air valve controlling the admission of air to the separate parts of said air chamber and a slot in said valve adapted to receive the partition.

13. A charge forming device for multi-cylinder internal combustion engines comprising a carburetor unit provided with a plurality of primary mixing chambers in which a primary mixture of fuel and air is formed, a manifold having a plurality of secondary mixing chambers formed therein and adapted to supply a combustible mixture to the engine intake ports, means for conveying the primary mixture to said secondary mixing chambers, a plurality of air passages in said manifold each of which supplies air to certain of said secondary mixing chambers only, a plurality of auxiliary air passages in the carburetor unit adapted to communicate with the air passages in said manifold, a primary air chamber for supplying air to the primary mixing chambers, a main air chamber for supplying air to all of said auxiliary air passages, a partition dividing the main and primary air chambers into separate parts communicating with different auxiliary air passages and different primary mixing chambers respectively, and a single valve controlling the flow of air on both sides of the partition.

14. An intake manifold for a multi-cylinder internal combustion engine comprising a plurality of outlet branches adapted to communicate with the engine intake ports, a plurality of air passages within the manifold each of which supplies air to certain of said outlet branches only, a plurality of inlet ports each of which admits air to one of said air passages, and means adapted to convey a primary mixture of air and fuel to the outlet branches of said manifold.

15. A charge forming device for a multi-cylinder internal combustion engine comprising, a plurality of mixing chambers, means for supplying fuel to said mixing

chambers, means for supplying air to said mixing chambers comprising a plurality of separate passages so constructed that communication between any one of said passages and some of said mixing chambers is prevented, and a common air inlet admitting air to all of said air passages.

16. A charge forming device for a multi-cylinder internal combustion engine comprising, a plurality of mixing chambers, means for supplying fuel to said mixing chambers, means for supplying air to said mixing chambers comprising a plurality of separate passages so constructed that communication between any one of said passages and some of said mixing chambers is prevented, and a single air valve controlling admission of air to all of said air passages.

17. A charge forming device for a multi-cylinder internal combustion engine comprising, a plurality of mixing chambers, means for supplying fuel to said mixing chambers, means for supplying air to said mixing chambers comprising a plurality of separate passages so constructed that communication between any one of said passages and some of said mixing chambers is prevented, a common air inlet supplying air to all of said passages, and a single suction operated air valve controlling the flow of air through all of said air passages.

18. A charge forming device for a multi-cylinder internal combustion engine comprising, a plurality of secondary mixing chambers, means for supplying a primary mixture of fuel and air thereto, means for supplying auxiliary air to said secondary mixing chambers, said means comprising a plurality of separate secondary air passages so constructed that communication between any one of said passages and some of the secondary mixing chambers is prevented, and a single air valve controlling admission of air to all of said secondary air passages.

45 19. A charge forming device for a multi-cylinder internal combustion engine comprising, a plurality of secondary mixing chambers, means for supplying a primary mixture of fuel and air thereto, means for supplying auxiliary air to said secondary mixing chambers, said means comprising a plurality of separate secondary air passages so constructed that communication between any one of said passages and some of the secondary mixing chambers is prevented, and a single air valve controlling the admission of air to all of said secondary air passages and to the primary mixture forming means.

60 In testimony whereof I hereto affix my signature.

FRED E. ASELTINE.
